G. CONSTANTINESCO

SPEED GOVERNOR

Filed May 21, 1925

Inventor
G. Constantinesco,
John Mira
by atty.

UNITED STATES PATENT OFFICE.

GEORGE CONSTANTINESCO, OF WEYBRIDGE, ENGLAND.

SPEED GOVERNOR.

Application filed May 21, 1925, Serial No. 31,967, and in Great Britain September 16, 1922.

The object of the invention is to make use of the pressure set up in a pipe containing liquid which is caused to surge to and fro, in speed governors. The pressure which varies as the square of the frequency is caused to act on a motor which operates any suitable form of throttling device or regulator.

Figure 1 illustrates the invention.

10 A crank *b* actuated by the prime mover, the speed of which is to be regulated, drives a pair of pistons *e f* in opposite phase by rods *c d*. The pistons work in cylinders *g h* which are connected by a pipe *21*. Two 15 inlet valves *k l* are situated in the cylinders beyond the travel of the pistons, and connect the cylinders with a source of fluid supply 23. The valves serve the double purpose of compensating for leakage and preventing 20 the pressure within the cylinders in their neighbourhood from falling below a certain normal amount which may be atmospheric pressure. At or near the middle point between the valves, where it is found that the 25 pressure has a constant value for a given frequency of the pistons, is an opening 25 leading to a pipe *71* which is connected to a cylinder *72* provided with a piston *73*. The piston is acted upon by a spring *74* and operates any suitable form of throttling or 30 regulating device (not shown) by means of a rod *76* supported, if necessary, by a guide 77.

Clearances are left as shown at *m* and *n* between the pistons *e* and *f* and their cylinders, and between the piston *73* and its cylinder as shown at 75. The object of these clearances is to allow fluid to leak past the pistons and allow the piston *73* to be moved by the spring *74*, otherwise the increase in 35 the volume of fluid within the system would prevent the piston *73* from resuming its original position after the frequency of the pistons *e* and *f* has decreased due to the governing action. 40

What I claim is:—

A speed governor for a prime mover, comprising in combination a pair of collinear fluid pressure cylinders, a pair of pistons working in the cylinders and actuated in 50 opposite phase by the prime mover, an inlet valve in each cylinder connecting it with a source of liquid supply, a pipe freely connecting the cylinders, a fluid pressure motor, means for operatively connecting the said 55 motor with the point midway between said valves, means for permitting leakage past the said pistons and the said motor, and means for connecting the said motor with a speed governing device. 60

In testimony that I claim the foregoing as my invention, I have signed my name this eighth day of May, 1925.

GEORGE CONSTANTINESCO.
